UNITED STATES PATENT OFFICE.

GERHARDT SIGVERT REHLING KAMPMANN, OF TEGAL, JAVA, DUTCH EAST INDIES.

DEVICE FOR SHARPENING SAFETY-RAZOR BLADES.

1,324,121.

Specification of Letters Patent.

Patented Dec. 9, 1919.

Application filed September 20, 1919. Serial No. 325,221.

To all whom it may concern:

Be it known that I, GERHARDT SIGVERT REHLING KAMPMANN, a subject of the Queen of The Netherlands, residing at Tegal, Java, 5 Dutch East Indies, have invented certain new and useful Improvements in Devices for Sharpening Safety-Razor Blades, of which the following is a specification.

This invention relates to a device for 10 sharpening safety razor blades (Gillette and the like) of the type whereby two sharpening rolls are rotated in the same direction while the blade is held between same in an inclined position in such manner that the 15 rolls are caused to act on the two cutting edges of the blade. In order to sharpen the blade at both sides the blade can be turned in the known manner, either by hand or automatically, after which the direction of the 20 rotation of the rolls should be reversed.

According to the present invention, there is provided a device of the character mentioned wherein improved means is employed for automatically turning the blade to insure 25 of the moving of the blade away from the rolls preparatory to the moving of the rolls, so that it is practically impossible to cut the rolls during the sharpening operation.

This result is obtained by the use of planetary pinions for driving the rolls, said pinions acting on a central wheel whereby the blade may be turned by hand about the axis of its clamping device and after this being 30 done the blade or an arm of the clamping device takes up the rolls these as a whole being rotated about the same axis at the same time rotating at a relatively high speed 35 about their own axes.

It is obvious that the condition of friction 40 of the various moving parts is material to the pressure exerted by the cutting edges of the blade on the rolls.

In the accompanying drawing the figures illustrate an embodiment, which is only 45 meant as an example.

Figure 1 is a perspective view of the device.

Fig. 2 is a sectional view through the axis.

Fig. 3 is a transverse section on the line A—B of Fig. 2.

Fig. 4 is a transverse section on the line C—D of Fig. 2.

Fig. 5 is a view similar to Fig. 3 of a 55 modified construction.

Fig. 6 shows a detail of the construction shown in Fig. 5.

The axles of the sharpening rolls *a* are provided with pinions *b*, which engage as planetary wheels the wheel *d*, the latter being secured to the bottom plate *c* of the casing of the device.

The roll supporting frame, in which the axles of the rolls are journaled consists of the two plates *e* and *s* which are connected 65 by four bolts *h*. The frame *e*, *s*, *h* is at one end pivoted about the trunnion of the blade-holder *g*, and at the other end about a concentric ring *f* on the fixed front wall *r* of the casing.

The blade holder *g* consists of two parts, the part *u* made in one piece with the journal and the part *o* to which the hand crank *i* is secured. The part *u* is channel formed and at one end provided with a collar *t*; 70 an arm *m* is secured to the other end. Said arm is provided with a hub portion *q* in which the part *o* fits. The part *u* is prevented from being removed out from the casing by the collar *t*. On the other hand 75 the part *o* may be drawn out of the casing readily. The part *o* is provided with two projections *v* adapted to fit into the usual openings of the razor blade and can be pushed into the apparatus through openings 80 *w* in the front wall *r*. As soon as the part *o* is fitted into the hub part *q* of the arm and the overhanging portion *p* of the fixed crank hub fits around the axle portion *u*, 85 the blade is clamped in its place and its cutting edges *k* and *l* may be pressed against the sharpening rolls *a*.

On turning the hand crank *i*, the edges *k* and *l* are pressed against the rolls, the latter are pushed back and forced to revolve 95 at a relatively high speed about their axes, at the same time the frame work *e*, *s*, *h* being forced to rotate within the casing. As soon as the blade is bent to a certain extent, the arm *m* comes into contact with one 100 of the projections *n* of the plate *e*. On turning the crank in the opposite direction, the blade first comes into contact with the rolls at the opposite sides before the latter may begin to rotate.

The arm *m* serves to maintain the frame work and rolls in proper position with respect to the axle *g* and the blade and also prevents excessive bending of the blade.

Fig. 5 is a view similar to Fig. 3 of a 110

modified construction, showing means for obtaining an exact adjustment of the blade axle g or the blade clamping device with respect to the rolls. Therefore the projections n are fixed to members n^1, n^2 , of sheet metal (one of same being shown in Fig. 6), said members being mounted rotatably upon the blade axle. Each of those members is made adjustable by means of a screw x secured in the plate e of the supporting frame e, s, h and a slot y in each of said members n^1, n^2 , so that an exact determination of the bending of the blade and of the pressure of the cutting edges of same on the rolls can be obtained.

Having now described and ascertained my invention, I declare that what I claim and desire to secure by Letters Patent is:

1. A device of the character described including a casing, a stationary gear carried concentrically of one end wall of the casing, a frame journaled in the casing and concentric of the gear, a blade holder having its axis rotatably mounted centrally of the end wall of the casing and concentric of the gear and frame, sharpening rolls provided with trunnions journaled in the frame, planetary pinions carried by the trunnions of the rolls and contacting with the stationary gear, means for rotating the blade holder and coöperative engaging means on the axis of the holder and on the frame and adapted to effect a connection between the holder and the frame for rotating the frame from the holder when the holder is rotated.

2. A device as claimed in claim 1 wherein the coöperative engaging means include projections carried by the frame, and an arm fixed to the axis of the blade holder for coacting with the projection to cause the

same to rotate about the axis of the blade holder during rotation of the latter.

3. A device as claimed in claim 1 wherein the coöperative engaging means consists of plates having their inner ends loosely arranged about the axis of the blade holder and the opposite ends adjustably connected with the frame so that they may be adjusted relative to each other, projections on said plates, and an arm fixed to the blade holder and designed to coact with either of the projections to in consequence cause the frame to rotate about the axis of the blade holder during rotation of the blade holder.

4. A device of the character described comprising a cylindrical casing, a stationary gear carried concentrically of the inner surface of one end wall of the casing, a concentric ring carried by the inner surface of the other end wall of the casing, a blade holding and clamping device having its axis journaled in the casing concentrically of the gear and the ring, a crank handle connected with the blade holding device for facilitating the rotation thereof, a frame surrounding the blade holder and having its respective ends journaled on the axis of the blade holder and on the concentric ring, sharpening rolls provided with trunnions journaled in the frame, planetary pinions carried by the outer ends of the trunnions of the rolls and coacting with the stationary gear, and coöperative engaging members on the axis of the blade holding and clamping device and on the frame for insuring rotation of the frame about the axis of the blade holding and clamping device during rotation of the latter.

In testimony whereof I affix my signature.

GERHARDT SIGVERT REHLING KAMPMANN.
